UNITED STATES PATENT OFFICE.

MATTHEW N. DU BOIS, OF PHILADELPHIA, PENNSYLVANIA.

SAW-SET.

SPECIFICATION forming part of Letters Patent No. 694,142, dated February 25, 1902.

Application filed April 14, 1900. Serial No. 12,952. (No model.)

To all whom it may concern:

Be it known that I, MATTHEW N. DU BOIS, a citizen of the United States, residing at Philadelphia, in the county of Philadelphia and State of Pennsylvania, have invented certain new and useful Improvements in Saw-Sets; and I do hereby declare the following to be a full, clear, and exact description of the invention, such as will enable others skilled in the art to which it appertains to make and use the same.

My invention relates to an improved construction of machine for setting the teeth of saws, and has for its object to produce a machine for this purpose wherein the parts are made adjustable, so as to adapt themselves to the teeth of saws which may vary in size, and wherein also the parts are so constructed and arranged that a uniformity of blow will be given to each tooth, thus resulting in a more perfect set than has been heretofore accomplished by the saw-sets at present in use.

My invention consists of a saw-set having an anvil disposed thereon in line with a plunger, means for withdrawing said plunger from said anvil and for releasing it, so as contact with the teeth of the saw during the operation of setting.

My invention further consists of the novel features of construction and arrangement of parts, all of which will be hereinafter fully described, and particularly pointed out in the appended claims.

Figure 1 represents a front elevation of a saw-setting machine constructed according to my invention, showing the position of the saw in dotted lines. Fig. 2 represents a side elevation thereof. Fig. 3 represents a vertical section taken on the line 3 3 of Fig. 2. Fig. 4 represents a detail perspective view of the plunger. Fig. 5 represents a detail section taken on the line 5 5 of Fig. 1, showing the anvil and means of adjusting it to suit saw-teeth of varying sizes. In this view the saw and the lower portion of the plunger are shown in their relative positions with the anvil; and Fig. 6 represents a sectional elevation taken on the line 6 6 of Fig. 1, showing the saw in elevation and the means employed for keeping it in its proper relation with respect to the anvil and plunger.

Similar reference-numerals indicate corresponding parts in all the figures of the drawings.

In said drawings, 1 designates the base of the machine, which may be of any desired size or configuration, said base being provided with a groove 2 to receive therein an adjustable anvil 3, upon which latter the saw will rest during the operation of setting the teeth.

4 designates a housing supported on legs 5, which are secured to the base 1 and between which the anvil 3 is located. The housing is provided with a centrally-disposed bore 7, within which the plunger 8 works, the latter being formed at its lower extremity with a triangular-shaped head, (to conform to the size and shape of the saw-tooth,) and its upper extremity is provided with an opening 10 to receive therein one end of the rod 11, the upper end of which is supported in a bushing 12, secured to the upper extremity 14 of the housing 4. A screw 15 serves to secure said bushing 12 in place.

16 designates a vertical slot formed in the wall of the housing 4, wherein one end of the screw 17 moves, the latter being adapted to pass through a threaded opening in the plunger 8 and an opening in the rod 11, so that the rod and plunger will move simultaneously, and the latter will be prevented from rotative movement by reason of the engagement of the screw 17 with the walls of the slot 16. By this construction it will be apparent that the plunger 8 may be quickly disengaged from connection with the rod 11 and another one substituted in instances where the teeth of the saw may vary in size.

18 designates a spiral spring interposed between the bushing 12 and the upper extremity of the plunger 8, the function of which is to force the plunger down upon the anvil during the operation of setting the teeth, as will be described later on.

The wall of the housing 4 upon its outside is provided with a pin or stud 19, upon which is mounted a wheel 20, the same being held in position by a nut 21, adapted to a threaded end 22 of the said pin or stud 19.

23 designates cam-blocks secured to the inner surface of the wheel 20, the same being adapted to engage the protruding end of the screw 17, as clearly shown in Figs. 1 and 2,

causing the plunger to rise against the action of the spring 18 until each cam-block shall have passed out of contact with said screw 17, when the plunger will be forced 5 down upon the tooth of the saw.

It will be observed by reference to Figs. 2 and 5 that the upper face of the anvil 3 is beveled more or less to suit varying conditions and that the inner adjoining ends of the 10 teeth rest upon the extreme uppermost part of said bevel, so that when the head of the plunger 8, which is also beveled, descends upon the tooth it will cause it to conform to such bevel.

24 designates adjustable supporting devices 15 whereon the body of the saw will rest during the operation of setting. These adjustable devices are preferably composed of screws 25, having enlarged heads 26, which may be raised or lowered at the will of the 20 operator, so as to give the saw the desired elevation.

I have provided means to compensate for the varying depths of the teeth of the saws, 25 said means being shown clearly in Figs. 1, 2, 3, and 6 of the drawings and consisting of slotted guides 27, against the forward bent extremities 28 of which the teeth of the saw will rest. These plates are secured to the legs 5 of the housing 4 by means of set-screws 29 30 and are adapted to move in either direction, so that the inner adjoining ends of the teeth may at all times be in line or approximately in line with the highest beveled surface of the anvil 3. It will be necessary to adjust 35 the anvil so as to accommodate itself to the adjustment of the guide-plates 27, and for that purpose I have provided the outer end of the anvil 3 with a threaded opening 30, adapted to receive therein the threaded shank of a 40 screw 31, the latter being supported in a bracket 32, secured to the base 1. Thus by revolving the screw it will be apparent that the anvil may be moved in either direction, so as to bring it into the desired position.

45 It will be apparent from the foregoing that by rotation of the wheel 20 by means of the handle 20^a the cam-blocks will be moved so as to rapidly engage the protruding end of the screw 17, thus causing the plunger to rise 50 and compress the spring 18, which after the screw 17 has been released by the cam-blocks 23 will cause the plunger to quickly descend upon the saw-tooth and conform it to the bevel of the plunger and anvil, as previously described.

Having thus fully described my invention, what I claim as new, and desire to secure by Letters Patent, is—

1. The combination in a machine of the character described of a base having a groove 60 in its upper surface, housing secured to the base, said housing having a vertical slot in one of its walls, a spring-pressed plunger operating in the housing, said plunger comprising a triangular-shaped head having an aperture 65 in its top and a rod which is secured to the plunger and has its lower end in engagement with the aperture of the head, a pin secured to the plunger and adapted to hold the parts together, said pin 70 working in and protruding beyond the slot of the housing, a power-wheel secured to the housing, cam-blocks secured to the inner face of the wheel and adapted to engage the protruding end of the said pin, an adjustable anvil 75 having its upper face beveled, said anvil being adapted to ride in the groove of the base, guide-plates on the legs of the housing, adjustable saw - supporting devices on the base, and operating means for the power- 80 wheel.

2. In a saw-set the combination with a base having a groove in its upper face, of an anvil adapted to slide in the said groove, the upper face of said anvil being beveled in opposite 85 directions from a central line, one end of said anvil having a threaded socket, a bracket fixed to the base, a screw working through the said bracket and entering the threaded socket of the anvil, and the vertically-adjustable rest-screws arranged upon the base upon opposite sides of the anvil, substantially as shown and described.

3. In a saw-set, the combination with a base, 90 of a housing arranged thereon and supported by suitable legs, an anvil adjustable upon the base, the vertical guides arranged upon the base adjacent to the anvil, the horizontal guides attached to the legs of the housing, the plunger having a socket in its upper end, 100 a spring-actuated rod working in the housing and connected to the plunger, the coupling pin for connecting the rod and plunger, the end of said pin projecting beyond the said plunger and working in a vertical slot produced in the side of the housing, and a wheel 105 having cam-lifting arms adapted to engage the said pin for the purpose of raising the plunger and the spring for forcing the plunger downwardly, substantially as set forth.

In testimony whereof I affix my signature in presence of two witnesses.

MATTHEW N. DU BOIS.
